DOOR LOCK

Headley Townsend Backhouse, London, England

Application November 1, 1938, Serial No. 238,134
In Great Britain December 2, 1937

13 Claims. (Cl. 292—169)

My invention relates to locks for doors or other closure members to which access may be had from both sides, and particularly for the inside doors of houses.

5 My improved lock according to the present invention comprises a bolt normally held in the latching position and two independently operable handles (one for each side of the door), each of which may be moved in one direction to force 10 the bolt into the unlatching position, or moved in the other direction to provide a positive stop for the bolt so that the latter becomes locked in its latching position.

The door-lock of my present invention is similar in principle to the door-locks usually employed on motor-cars with the important difference that with the motor-car door-locks only the inside handle can be moved into a locking position, while with my improved lock of this 20 invention the handle on either side may be moved into the locking position so that when one handle is in the locking position, the lock cannot be opened by the handle on the opposite side of the door.

25 The door-lock of my invention is particularly useful for the inside doors of houses, for example, the doors leading from living rooms to a central hall or corridor, since on the one hand the occupants of the room may lock the door 30 by a simple operation, and on the other hand as a precaution against burglars, the door may be locked from the outside of the room so that any person breaking into the room through the window would experience considerable difficulty 35 in making his way into the hall and to other parts of the house.

In certain circumstances, for example, when this lock is intended for use on a door leading from a living room into a central hall, it is desirable 40 that it should not be possible to move both handles into the locking position at the same time since this might well prove both inconvenient and dangerous. My improved lock therefore preferably includes means for preventing the 45 bolt being locked in its latching position from both sides of the door. For example, the positive stop associated with one handle may be arranged, when in the locking position, to form an abutment which prevents the stop associated 50 with the other handle from being moved into the locking position.

Several specific embodiments of door-locks embodying my invention will now be described by way of example, and with reference to the accompanying drawings, in which:

Figure 1 is a perspective view of a rim lock intended for attachment to the face of a door, the casing of the lock being shown in chain lines;

Figure 2 is a plan view, partly broken away, showing the lock of Figure 1 in position on the door;

Figure 3 is a view showing one handle and the bolt in latching position;

Figure 4 is a view showing the bolt locked in its unlatching position;

Figure 5 is a view similar to Figure 3, but showing detent means for retaining the handle in the locking position;

Figure 6 is a view similar to Figure 5, but showing an alternative form of detent means;

Figure 7 is a perspective view, partly in section, of a mortice lock embodying my invention;

Figure 8 is a view of a detail of the lock shown in Figure 7, both handles being in their latching 20 but unlocked position;

Figure 9 is a plan view, partly in section, of another form of mortice lock;

Figure 10 is an elevation showing the working parts of another alternative form of mortice 25 lock;

Figure 11 is a plan view, partly in section, of the lock shown in Figure 10;

Figure 12 is an elevation showing the working parts of another form of mortice lock embodying 30 my invention;

Figure 13 is a plan view, partly in section, of the lock shown in Figure 12;

Figure 14 is a sectional view taken on the line 14—14 in Figure 12;

Figure 15 is a detail of a modification of the lock shown in Figures 13 and 14, this modification also being applicable to the lock shown in Figures 10 and 11.

Figure 16 is an elevation showing the working parts of another form of mortice lock embodying 40 my invention; and

Figure 17 is a sectional view taken on the line 17—17 of Figure 16.

Similar numerals refer to similar parts 45 throughout the several figures.

Referring to the form of my improved lock shown in Figs. 1-6, the lock as a whole is contained within the rectangular frame 18 having two separable closure plates 19 and 20, the plate 50 20 being of larger area than the frame 18 to provide the flange 21 by which the lock is attached to the door 22 by screws 23 (Figs. 1 and 2). The lock contains the slideable bolt 24 and two independently operated handles 25 and 26 that 55

are carried on the sleeves 27 and 28 respectively, which are mounted for rotation on the supporting spindle 29. The sleeves 27 and 28 have secured to them the crank arms 30 and 31 respectively, the arms 30 and 31 carrying the pins 32 and 33 respectively that project from the arms in a direction parallel with the spindle 29. Both pins 32 and 33 are arranged to cooperate with the slot 34 formed in the rear end of the bolt 24 both for forcing the latter into its unlatching position and also for locking the bolt 24 in the latching position.

The slot 34 is provided with the flat bearing surface 35 that is substantially parallel with the rear edge 36 of the bolt 24, against which surface 35 the pins 32 and 33 press when the associated handles 25 and 26 are actuated. For example, in Fig. 4 I have shown the pin 33 bearing against the bolt 24 against the action of the spring 36A 15 to force the bolt 24 into unlatching position. The slot 34 is so shaped, however, that the handle 26 may be turned in the opposite direction (Fig. 3) so that the pin 33 and arm 34 lie in the direction of the outward movement of the bolt 24 and the pin 33 engages the bearing surface 37 oppositely disposed to the bearing surface 35. In 20 this position (Fig. 3), the pin 33 acts as a positive stop to prevent the bolt 24 from being forced into its unlatching position, and consequently 25 prevents the lock from being unlatched by the 30 operation of the other handle 25.

To ensure that once the pin 33 has been moved into the locking position (Fig. 3), it will remain in such position until the handle 26 is actuated to unlock the bolt 24, the bearing surface 37 is provided with the recess 38. The spring 39 is employed to draw the bolt 24 in the unlatching direction, such means as a whole forming a detent to hold the pin 33 in the recess 38.

40 The supporting spindle 29 is secured in the pillar 40 fastened to the frame 18 (Fig. 1). To ensure that it shall not be possible to move both handles 25 and 26 into locking position at the same time, the sleeves 27 and 28 are provided
45 with internal screw-threads 41 and 42 respectively of quick pitch that engage corresponding threads on the spindle 29. The threads 41 and 42 are left and right handed respectively, and are so arranged within the lock (Figs. 1 and 2) that as either handle 25 or 26 is moved into locking position, the corresponding sleeve 27 or 28 and with it the associated crank pin 32 or 33 is moved inwardly into the bolt 24 within the slot 34 so that such pin lies in the path which would
50 be followed by the other pin (32 or 33) associated with the other handle. For example, Fig. 2 shows the pin 33 in the locking position against the bolt 24 and such pin 33 extends beyond the center line of the bolt far enough to form a stop
55 to prevent the movement of the pin 32 into locking position. It is obvious that the pin 32 will also, when moved toward the locking position, move to the left in Fig. 2 by the inward movement of the sleeve 27 on the spindle 29. Likewise if
60 the pin 32 is moved towards its locking position, it will be possible to move such pin 32 back to the free position by operating the handle 26 which will cause the pin 33 to engage the pin 32 and move the latter in the unlocking direction until
65 the two pins 32 and 33 are axially separated.
70

To assemble the lock shown in Figs. 1 and 2, the spindle 29 is first fixed in position on the pillar 40, and then the two sleeves 27 and 28 are screwed on the spindle 29. The bolt 24 with its associated springs 36A and 39 and the support-

ing bracket 43 are then placed in position, and finally the two cover plates 19 and 20 are threaded over the sleeves 27 and 28, the handles 25 and 26 being preferably secured in position on their respective sleeves after the lock has been attached to the door 22. 5

In place of the detent arrangement shown in Figs. 1-4 for holding the pins 32 and 33 in their locking positions, I may employ equivalent devices such as are shown in Figs. 5 and 6. In Fig. 5 the spring-loaded ball 44 carried by the bolt 24 is used to retain the pins 32 or 33 in their locking position. In Fig. 6 the small leaf spring 45 is employed over which the pins 32 or 33 ride into locking position as shown. 15

Another form of my improved lock according to the present invention is shown in Figs. 7 and 8 as a mortice lock. In this form the crank pins 32 and 33 cooperate with the bearing surfaces 35 and 37 on the bolt 24 in the same manner as in the Figs. 1-6 construction for moving the bolt 24 into either its locking or unlatching positions. The crank pins 32 and 33 are actuated by their respective handles 25 and 26. However in this Figs. 7 and 8 lock structure, the sleeves 27 and 28 of the Figs. 1-6 lock are replaced by short bosses 48 and 49 which are held in recessed bosses 46 and 47 respectively formed on the interior faces of the cover plates 19A and 21A respectively. The bosses 48 and 49 each have a centrally-disposed, rectangular-sectioned bore, and the handles 25 and 26 are fastened to the shafts 52 and 53 respectively which have their inner ends formed with squared portions as shown at 54 in respect of shaft 52 that fit inside the bores formed in the bosses 48 and 49. The central spring 56 surrounds extensions on the bosses 48 and 49 and engages the crank arms 30 and 31 thereby tending to hold the bosses 48 and 49 in axially separated position.

The bosses 46 and 48 carry coacting cam surfaces 57 and 58 respectively (Fig. 8), so arranged that as the handle 25 is moved into the locking position, the boss 48 and the associated pin 32 are moved axially toward the boss 47 so that when in locking position the pin 32 lies in the path of the pin 33 and prevents the latter from being moved into locking position. If desired the bosses 47 and 49 may also be provided with similar coacting cam surfaces as shown for the bosses 46 and 48. However, such construction is not essential, since the desired result of preventing locking from both sides of the door simultaneously may be obtained with only one pair of cam surfaces 57 and 58 as shown.

To place this Figs. 7 and 8 lock on the door 22, the handles 25 and 26 are removed together with their shafts 52 and 53. The lock is then placed in the mortice in the usual way, and the handles replaced with the shafts 52 and 53 60 threaded in their respective bosses 48 and 49. The handles 25 and 26 are held in position by plates 50 and 51 fastened to the outer faces of the door 22.

A modified form of lock such as is shown in Figs. 7 and 8 is illustrated in Fig. 9. In this modification the co-operating cam surfaces 57 and 58 are omitted so that no axial movement of the crank pins 32 and 33 takes place, and the locking of the door 22 from both sides simultaneously is prevented by means of a swinging member 61. This member 61 is mounted on the pivot 62 carried by the bolt 24 at a position where the member 61 will be engaged by the crank pins 32 and 33 as they are moved into 75

locking position. For example, when the crank pin 32 is moved into locking position, it engages the member 61 at the rounded-portion 63 and swings the member 61 about the pivot support 62 to move the other rounded portion 64 of the member 61 into the path of the crank pin 33 thereby preventing the latter from being moved into locking position by the handle 26. The spring 65 carried by the bolt 24 engages the lower end of the member 61 normally to return the latter into its central position when the pins 32 and 33 are moved from their locking position.

Another embodiment of my invention is shown in the lock illustrated in Figs. 10 and 11, which form of lock also prevents the bolt 24 from being locked from both sides of the door 22 simultaneously. In this embodiment, the movement of the bolt 24 is effected by means of the rocking arms 66 and 67 carried on the square spindles 68 and 69 respectively, to which the handles 25 and 26 are fastened. The arms 66 and 67 are adapted to engage the bearing surface 70 formed on the bolt 24, and when the arms 66 and 67 are rotated in a clockwise direction (Fig. 10), they move the bolt 24 into its unlatching position. The locking of the bolt 24 in the latched position is effected by the movement of the arms 66 and 67 in an anti-clockwise direction shown by chain lines in Fig. 10. As each arm 66 or 67 is so moved into the locking position, it engages the pawl 71 common to both arms and supported on the pivot 72 from the casing and rotates the pawl 71 from the full-line position shown in Fig. 10 to its chain line position so that the upper end 73 of the pawl 71 is moved into the path of the other arm (66 or 67) to prevent such other arm from being rotated into the locking position. The spring 74 carried by the casing bears against the pawl 71 tends to return the pawl 71 into the full-line position when the arm is brought to its unlocking position. To aid in locating the two arms 66 and 67 in position on their square sectioned spindles 68 and 69 respectively, I have provided the locating pin 75 that extends into the ends of the spindles 68 and 69. This pin 75 is circular in cross-section, and is provided with the washer 76 arranged between the arms 66 and 67. The washer 76 is preferably integral with the pin 75 and made of suitable anti-friction metal, and such washer 76 is of smaller diameter than the bosses carrying the arms 66 and 67. The inner faces of such bosses are recessed to contain the washer 76, the thickness of the latter being sufficient to prevent contact between the rims of the oppositely disposed bosses of the arms 66 and 67, all as shown in Fig. 11. A compression spring 77 carried on the guide pin 78 and engaging the rear end of the bolt 24 acts to restore the bolt 24 into the latching position (Fig. 10).

Figures 12-14 show another embodiment of my improved lock for preventing the door 22 being locked from both sides simultaneously. In this embodiment such means comprise the ball 79 located in the transverse passage 80 formed in the upstanding web 81 on the bolt 24. This ball 79 is moved from one side of the web 81 to the other side by the members 82 and 83 integral with the arms 66 and 67 which are constructed and operate as in the form of lock shown in Figs. 10 and 11. In Figs. 12-14 lock the arm 67 is shown in the locking position and its integral extension 83 has pushed the ball 79 into the path of the extension member 82 of the

other arm 66. When the arm 67 is moved to the unlocking position, the ball 79 assumes a central position on the curved flange 84 of the bolt 24 in readiness to be pushed to either side of the lock as one or the other of the arms 66 and 67 is moved into locking position.

In place of the locating pin 75 and washer 76 shown in the embodiments illustrated in Figs. 10-14, I may employ the arrangement shown in Fig. 15 which comprises the disk 85 having the rounded stud 86 projecting from one side. The plain face of the disk is secured to the inner face of one of the arms 66 or 67, such disk 85 being of suitable diameter to fit freely into a circular recess on the inner face of the boss on the other arm 66 or 67, as the case may be, with the thickness of the disk 85 greater than the recess to separate the bosses of the two arms 66 and 67. The stud 86 fits freely into an axial bore formed in the square section spindle (68 or 69) which operates the opposite arm (66 or 67).

In Figs. 16 and 17 I have shown another embodiment of my mortice lock in which the square-sectioned spindles 68 and 69 (Figs. 10-15) are provided with axial holes 87 and 88 formed throughout their length, or such spindles may be constructed as square section tubes 89 and 90. The washer 76 carries no integral pin, but is held in position (Fig. 17) by recesses formed in the rims of the bosses of the arms 66 and 67. After placing this form of lock in the door 22, the tubes 89 and 90 are inserted together with the rounded bar 91 which has an easy fit within the tubes 89 and 90. Such bar 91 is slightly shorter (Fig. 17) than the passage formed by the washer 76 and the tubes 89 and 90. The handles 25 and 26 are then attached to the tubes 89 and 90 in the usual way, such handles being held in position by the cover plates 59 and 60. The shoulders of the handles 25 and 26 retain in place the bar 91 which acts to keep the lock assembly in coaxial alignment and also to prevent the development of any backlash. I also may provide the arms 66 and 67 with the shoulders 92 and 93, either of which may be engaged by the screw 94 fastened in holes 95 and 96 formed in the rear end of the casing. When the screw 94 is inserted in either of the holes 95 or 96 it will engage either of the shoulders 92 or 93 and prevent the corresponding arms 66 or 67 from being moved into the locking position. Such embodiment as shown in Figs. 16 and 17 enables my lock, without any substantial alteration in design or manufacture to be used under conditions requiring that the door 22 may be positively locked from one side only. This form may be desirable where a set of standard locks are used and where it becomes important that the doors of one or more rooms should not be accidentally locked from the outside thereby preventing the occupants from leaving the rooms.

I claim as my invention:

1. A door-lock having in combination a bolt normally held in latching position, independently operable handles on either side of the door, and separate means operatively connected with each handle movable in one direction to force the bolt into unlatching position, each of said means when moved in the opposite direction to engage the bolt to form a positive stop to lock the bolt in its latched position.

2. A door-lock having in combination a bolt normally held in latching position, independently operable handles on either side of the door, separate means operatively connected with each han- 75

idle movable in one direction to force the bolt into unlatching position, each of said means when moved in the opposite direction to engage the bolt to form a positive stop to lock the bolt in its latched position, and means for preventing the bolt being locked in its latched position simultaneously from both sides of the door.

5. A door-lock as claimed in claim 1 in which the means operatively connected with each handle comprises a rotatable and axially movable shaft and an offset crank pin on said shaft to engage said bolt when the handle is in locking position whereby the contact point of said pin on the bolt and the axis of the shaft lie in alignment with the movement of said bolt, said pin affording a stop for the bolt.

10. A door-lock as claimed in claim 1 in which the means operatively connected with each handle comprises a rotatable and axially movable shaft and an arm on said shaft to engage said bolt when the handle is in locking position whereby the contact point of said arm on the bolt and the axis of the shaft lie in alignment with the movement of said bolt, said arm affording a stop for the bolt.

15. A door-lock as claimed in claim 1 in which the means operatively connected with each handle comprises a rotatable and axially movable shaft and an offset crank pin on said shaft to engage said bolt when the handle is in locking position whereby the contact point of said pin on the bolt and the axis of the shaft lie in alignment with the movement of said bolt, said pin affording a stop for the bolt, and means connected with said handle when moved in the unlatching direction to force the crank pin against the bolt to unlatch same.

20. A door-lock as claimed in claim 1 in which the means operatively connected with each handle comprises a rotatable and axially movable shaft and an arm on said shaft to engage said bolt when the handle is in locking position whereby the contact point of said arm on the bolt and the axis of the shaft lie in alignment with the movement of said bolt, said arm affording a stop for the bolt, and means connected with said handle when moved in the unlatching direction to force the arm against the bolt to unlatch same.

25. A door-lock having in combination a bolt normally held in latching position, independently operable handles on either side of the door, and separate means operatively connected with each handle movable in one direction to force the bolt into unlatching position, each of said means when moved in the opposite direction to engage the bolt to form a positive stop to lock the bolt in its latched position, said stops being so disposed that each forms an abutment to prevent the

other stop from being brought simultaneously into operative position.

3. A door-lock having in combination a bolt normally held in latching position, independently operable handles on either side of the door, means operatively connected with each handle comprising a rotatable shaft, means on each shaft to engage said bolt when in its latched position, and means associated with one of said shafts when rotated into locking position to move said shaft axially to bring said bolt-engaging means into position to prevent the bolt-engaging means on the other shaft being moved into locking position.

4. A door-lock having in combination a bolt normally held in latching position, independently operable handles on either side of the door, separate means operatively connected with each handle movable in one direction to force the bolt into latching position, and a stop member automatically movable as either of said means approaches locking position into the path of the other said means to prevent the latter means from being moved into locked position.

5. A door-lock having in combination a bolt normally held in latching position, independently operable handles on either side of the door, means operatively connected with each handle movable in one direction to lock the bolt in the latching position, and interchangeable means to prevent either of said locking means from being moved into locking position.

10. A door-lock having in combination a bolt normally held in latching position, independently operable handles on either side of the door, means operatively connected with each handle movable in one direction to force the bolt into unlatching position, each of said means when moved in the opposite direction to engage the bolt to form a positive stop to lock the bolt in its latched position, and detent means for holding at least one of the handles in locked position.

15. A door-lock as claimed in claim 9 in which the stop member comprises a ball transversely movable in the lock and a member associated with each handle, said ball and members being arranged that when either handle is moved into locking position the ball is thereby moved into the path of the member associated with the other handle.

20. A door-lock as claimed in claim 9 in which the stop member comprises a pivoted lever and arms movable with said handles, said lever and arms being arranged that when either handle is moved into locking position said lever is moved by the arm into the path of the other arm movable with the other handle.

HEADLEY TOWNSEND BACKHOUSE.
